AMUSEMENT RIDE CAR

Joseph W. Fowler, Corona Del Mar, Calif., assignor to Disneyland, Inc., Anaheim, Calif., a corporation of California

Filed Mar. 21, 1960, Ser. No. 59,812

Term of patent 14 years

(Cl. D34—15)

I claim:

The ornamental design for an amusement ride car, substantially as shown.
